Fig. 1.

Fig. 2.

Fig. 3.

Fig. 4.

Figure 1 is a perspective view of an Ottoman embodying my new design, as seen from one side thereof, the appearance of the Ottoman being similar when viewed from the other side.

Figure 2 is a perspective view of the same as viewed from the right side thereof.

Figure 3 is an exploded perspective view of the same revealing the appearance of the removable cushion and of one side of the removable cushion-supporting panel; and

Figure 4 is a plan view of the side of the cushion-supporting panel opposite that shown in Figure 3.

The characteristic features of the design reside in the portions shown by means of full lines in the drawing.

I claim:

The ornamental design for an Ottoman, as shown and described.
